UNITED STATES PATENT OFFICE

2,639,020

CONTROLLED NOISE-REDUCTION MEANS
FOR TYPEWRITERSCharles Schroder, West Hartford, Conn., assignor
to Underwood Corporation, New York, N. Y., a
corporation of Delaware

Application December 23, 1949, Serial No. 134,703

11 Claims. (Cl. 197--186)

1

This invention relates to controlled noise-reduction means for typewriters and more particularly to noise-reduction means in association with mechanical-vibration and safety controls.

Objectionable noise in typewriter operation stems in most instances from the following causes: type-bar impact against the paper on the platen, carriage arrest in tabulation and return, case-shifting of the type-basket, the escapement mechanism in its letter feed operations, and the bottoming of the space-bar against a limiting stop. In power-driven typewriters some of these noises may be accentuated and the electric motor may itself set up sound vibrations capable of transmission to the desk or platform on which the machine is mounted and to other panels or parts of the machine where the noise may be intensified.

Efforts have been made over a long period to

cause of the continuous precision required during the life of the machine and the failure of the devices, in the manner they have been used, previously, to maintain a uniform condition, owing to oxidation, wear, matting and other reasons.

The present invention has as one of its objects to provide a novel assembly of a typewriter base, mask, and a frame carrying the working parts, which results in a great amount of damping of sound vibrations and controls the mechanical vibrations of the working parts of the machine to the end that the working parts function continuously as intended and as necessary to proper typewriter operation and results.

Another object of the invention is to provide, in association with such devices for damping or deadening the sound vibrations, certain safety means for preventing the straining or breaking of parts which might otherwise be so affected by use following the introduction of the noise-re-

2

ducing means.

It is a further object of the invention to minimize the possibility of the outer masked panels of the typewriter becoming sounding boards and propagating transmitters for sounds originating in the working mechanism of the machine, and to generally deaden the noises created by all impacts of the working parts without setting up such mechanical vibrations as would affect the accuracy of their operations or cause objectionable dance or shimmy of the carriage parts.

Other objects will be in part obvious and in

part indicated by these mechanisms in their normal operation and to avoid intensification of the sound by interfering with or deadening the sound vibrations before they reach parts of the machine or the machine mounting which have special sound-transmitting characteristics. Many difficulties have been encountered in the attempts to improve typewriters in these respects. Many rubber-foot ideas and mountings of various mechanisms on springs or in rubber or felt or the like have been tried and discarded, principally because of their failure to obtain the desired noise

silient material for holding the base generally spaced from a platform, a mask supported from said base comprising upstanding closure panels, a skeleton frame within said mask having mounted thereon the following: a platen carriage, a set of type-bars, means for driving said platen carriage, comprising an electric motor and transmission devices; means mounting the frame on the base comprising a plurality of sound-deadening diaphragms which hold the skeleton frame, and the parts mounted thereon, otherwise normally spaced from the base and the mask and allow for typing and platen-carriage movements effected by the motor, and cushion-stop-means in part on said base and in part on said frame for determining the maximum amplitude of vibratory movement of the frame, relative to the base, permitted by said diaphragms.

10. A machine of the class described comprising a base having supporting members of resilient material for holding the base generally spaced from a platform, a mask supported from said base comprising upstanding closure panels, a skeleton frame within said mask having mounted thereon the following: a platen carriage, a set of type bars, means for driving said type-bars, for case-shifting and for moving said platen carriage, comprising an electric motor and transmission devices; means mounting the frame on the base comprising a plurality of sound-deadening diaphragms which hold the skeleton frame, and the parts mounted thereon, otherwise normally spaced from the base and the mask and allow for typing and platen-carriage movements effected by the motor, cushion-stop-means in part on said base and in part on said frame for determining the maximum amplitude of vibratory movement of the frame relative to the base permitted by said diaphragms, and certain of said diaphragms being located in

5 a line substantially between the said motor and certain of said resilient base-supporting members.

11. A typewriter comprising a substantially horizontal base, a mask supported solely from said base and including upstanding closure panels, a skeleton frame within said mask and supporting an escapement-controlled paper carriage and type bars and other operating parts of the typewriter, said frame presenting horizontally a generally rectangular outline, a plurality of rubber-in-shear diaphragms mounting the frame on the base, there being one said diaphragm adjacent each of the four corners of the rectangular frame outline, said diaphragms holding the frame normally generally spaced from the base and from the mask, with a capability of vertical vibratory and tilting movements of the frame relatively to the base, and a vibration-control device arranged intermediate the two diaphragms at each side of the frame and including an adjustable stop means in part on the frame and in part on the base for variably determining the maximum amplitude of vertical vibrations and tilting movements of the frame.
